(74) Attorney, Agent, or Firm — Fross Zelnick Lehrman & Zissu, P.C.; Lawrence E. Apolzon, Esq.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing our new design. The broken line showing of the display screen or portion thereof is not part of the claimed design.
